UNITED STATES PATENT OFFICE.

WILLIAM N. HALL, OF WOODBURN, IOWA.

CAR-COUPING.

SPECIFICATION forming part of Letters Patent No. 498,789, dated June 6, 1893.

Application filed March 8, 1893. Serial No. 466,186. (No model.)

To all whom it may concern:

Be it known that I, WILLIAM N. HALL, a citizen of the United States, residing at Woodburn, in the county of Clark and State of Iowa, have invented certain new and useful Improvements in Car-Couplers; and I do hereby declare the following to be a full, clear, and exact description of the invention, such as will enable others skilled in the art to which it appertains to make and use the same.

This invention relates to a new and useful improvement in car couplers and it consists in the construction and arrangement of parts hereinafter described and definitely pointed out in the claim.

The object of this invention is the provision in car couplers of means by which the cars are held firmly and securely in a coupled position and are easily uncoupled, also uniting simplicity and cheapness of construction. These objects are obtained by the construction illustrated in the accompanying drawings wherein like letters of reference indicate corresponding parts in both the views and in which—

Figure 1 is a perspective view of an end of a car showing my improved coupler. Fig. 2 is a horizontal section of the draw bar and head.

30 In the drawings A represents the car and B the drawbar.

F is an aperture in the top and bottom of the drawhead.

Within the drawhead is secured the coupling hook E, by means of the vertical hollow bar E' secured at right angles to the coupling hook and the pin F' which passes through the aperture F in the drawhead and through the hollow bar E' on the coupling hook. The 40 hollow bar E' is of a length long enough to allow it to fit snugly into the drawhead and when the pin F' is passed through the aperture F in the drawhead and the hollow bar the coupling hook will be held firmly and securely in position. By this construction the coupling hook is prevented from having any but a sidewise or right and left movement.

On the side of the drawhead is a cylindrical casing K having a cap K' formed with

an enlarged aperture G' therein. The drawing rod G passes through the aperture G' in the cap K' in the side of the drawhead and at its outer end is bent at right angles and slidingly secured to a loop H on the vertical lever H' extending from above the top of the car and secured thereto by means of the securing brace I, extending outward from the front of the car, which also serves as a fulcrum.

L is a notched segment secured to the front of the car by means of suitable bolts L' and M is a spring pawl secured to the lever H' in any suitable manner the teeth M' of which engage the notch segment L.

O is a coil spring on the rod G resting on the side of the coupler hook and the cap K' on the casing on the side of the drawhead. This coiled spring is so arranged that by its expansion it will tend to force the coupler hook in and hold the same in a parallel position with the side of the drawhead, and thus firmly engage with the coupler hook of the adjacent car. It will be seen that by moving the lever H' either to the right or left the rod G will be moved sidewise thereby parting 75 the coupler hooks and uncoupling the cars. By having the drawing rod G slidingly connected to the vertical lever H' when the cars are to be coupled, the coupling hook E can engage the hook on the adjacent car without 80 moving the vertical lever H' the coiled spring resting on the side of the coupling hook by its tension will force the coupling hooks together thereby automatically coupling the cars.

Having thus described my invention, what I claim as new, and desire to secure by Letters Patent, is—

In a car coupler, the combination of a drawhead, having an aperture in the top and bottom thereof, a coupling hook, a vertical hollow bar secured to the coupling hook at right angles thereto, a pin passing through the apertures in the drawhead and hollow bar, a cylindrical casing on the side of the drawhead, an apertured cap on the casing, a horizontal drawing rod secured to the coupling hook, a spring on the drawing rod between

the coupling hook and cap on the casing, a right angle extension on the drawing rod formed integral therewith, a lever extending from above the car slidingly secured thereto, 5 a notched segment on the car and a spring pawl on the lever engaging the segment, substantially as described.

In testimony whereof I affix my signature in presence of two witnesses.

WILLIAM N. HALL.
